UNITED STATES PATENT OFFICE

150,408

DESIGN FOR A COCKTAIL TABLE

Walter Dziewit, Detroit, Mich.

Application February 8, 1947, Serial No. 136,773

Term of patent 3½ years

(Cl. D33—14)

To all whom it may concern:

Be it known that I, Walter Dziewit, a citizen of the United States, residing at Detroit, in the county of Wayne and State of Michigan, have invented a new, original, and ornamental Design for a Cocktail Table, of which the following is a specification, reference being had to the accompanying drawing, forming part thereof, in which:

Fig. 1 is a plan view of a table, showing my design.

Fig. 2 is a side elevational view thereof; and

Fig. 3 is a bottom plan view thereof.

I claim:

The ornamental design for a cocktail table, substantially as shown.

WALTER DZIEWIT.
